United States Patent Office.

LEWIS C. TOWER, OF ROCHESTER, NEW YORK.

Letters Patent No. 66,266, dated July 2, 1867.

IMPROVEMENT IN THERMOMETERS.

The Schedule referred to in these Letters Patent and making part of the same.

TO ALL WHOM IT MAY CONCERN:

Be it known that I, LEWIS C. TOWER, of Rochester, in the county of Monroe, and State of New York, have invented certain new and useful Improvements in Thermometers; and I do hereby declare that the following is a full and exact description thereof, reference being had to the accompanying drawings, making part of this specification.

Figure 1 is an elevation of my improved thermometer.

Figure 2, a section of the same.

Figure 3, an elevation of a modification, showing the frame wired.

Figure 4, a section of the same.

Like letters of reference indicate corresponding parts in all the figures.

My invention consists, essentially, in corrugating or stamping the frame so as to produce greater stiffness and strength; also, in providing a groove or socket for the reception of the bulb and tube, so that the same will be sunk flush with the surface of the frame in front, and be protected by the metal in the rear; and, furthermore, in the employment of a shield over the bulb, which is made to slide up so as to allow the bulb to be inserted in any liquid to indicate the temperature without wetting the shield.

As represented in the drawings, A is the frame to support the ordinary tube B and bulb a. This frame is "struck up" or stamped by dies, so as to form corrugations b b b longitudinally, as clearly shown in figs. 1 and 2. In the centre is struck a groove or socket, c, of a form corresponding with that of the tube and bulb, which are sunk therein flush with the surface. The frame is provided with a convex shield, d, which rests over the bulb in front. I make this shield to adjust up and down in slots f f cut longitudinally through the frame, or in some equivalent manner.

It is found necessary to make the frames of thermometers very stiff, as a slight bend or spring is sufficient to break the slender glass tube attached thereto. To insure this stiffness, ordinary thermometers are made of a case, in which rests a slide having the glass tube attached, and on which the scale is cut. The frame is thus made up of two parts, and is expensive, and besides, is difficult to keep clean. I form my frame of but a single piece of sheet metal, which is made sufficiently stiff to prevent springing by the corrugations, as before described. With the sides thus struck out, the frame will resist any ordinary strain and serve as a complete protective to the brittle stem of glass. This form is exceedingly simple and effective, and I thus avoid the great expense of a frame which is made of parts and must be soldered together. Being thus in a single plain piece, the frame is in condition to be inserted in any liquid, such as cream, and can be easily cleaned, which is not the case with the ordinary frame. The inserting of the glass tube and bulb in the groove c not only preserves it from injury in front, by sinking it beneath the surface, but also on the back, by presenting an enclosed bed of the metal. In ordinary thermometers the bulb rests in a hole bored through the support. The shield d not only serves as a protection to the bulb in front, but by making it to slide up, it enables me to insert the bulb and the lower part of the tube in any liquid to test the temperature without wetting the shield; and, since the frame is plain and in a single piece, as before described, it is very easily cleaned. In ordinary thermometers a substitute for the shield is made in the form of a fixed box at the bottom, which extends above the bulb; but such devices cannot be inserted in liquid, as before described, without filling the box; neither can it be placed out of doors in snowy weather without filling with snow. For some uses I prefer to wire the edges of the frame, as indicated in figs. 3 and 4. In this form it is easily handled in inserting in liquid. It is obvious that the edges of the frame may be bent out to give additional stiffness with a similar effect.

What I claim as my invention, and desire to secure by Letters Patent, is—

1. A thermometer whose frame is made from a single piece of sheet metal, corrugated, as described, to give it stiffness, and provided with a groove and socket to receive the tube and bulb, substantially as herein set forth.
2. The combination of the sliding shield d with the frame A and bulb a, as and for the purpose specified.

In witness whereof I have hereunto signed my name in the presence of two subscribing witnesses.

LEWIS C. TOWER.
